TIRE

Raymond P. Hawkinson, Minneapolis, Minn., assignor to
Paul E. Hawkinson Company, Minneapolis, Minn., a
corporation of Minnesota

Filed Apr. 25, 1966, Ser. No. 1,995

Term of patent 14 years

(Cl. D90—20)

FIG. 1 is a fragmentary view in elevation of a tire showing my new design, it being understood that the full line portions are repeated throughout the circumference of the tire shown by means of broken lines; and

FIG. 2 is a view in transverse section thereof as seen from the line 2—2 of FIG. 1.

FIG. 3 is a fragmentary view in side elevation thereof as seen from the line 3—3 of FIG. 1, the opposite side thereof being substantially a mirror image.

The dominant features of my design reside in the portions shown in full lines.

I claim:

The ornamental design for a tire, substantially as shown and described.
